JUG SUPPORT OR THE LIKE

Lynn P. Carlson, Cincinnati, Ohio

Application February 21, 1958, Serial No. 49,743

Term of patent 14 years

(Cl. D58—26)

Fig. 1 is a front perspective view of a jug support or the like, showing my new design.

Fig. 2 is a side view thereof.

Fig. 3 is a sectional view on line 3—3 of Fig. 1.

Fig. 4 is a sectional view taken on line 4—4 of Fig. 1.

I claim:

The ornamental design for a jug support or the like, as shown.
